CLAIM

The ornamental design for a maternity gown, as shown and described.

DESCRIPTION

FIG. 1 is a front view for a maternity gown showing our new design.

FIG. 2 shows the front view for the first embodiment, where a right shoulder strap has been unbuttoned.

FIG. 3 shows the front view for the first embodiment, where a left shoulder strap has been unbuttoned.

FIG. 4 shows the front view for the first embodiment, where the right and left shoulder straps have been unbuttoned.

FIG. 5 shows the front view for the first embodiment, where an upper layer of a flap opening has been opened.

FIG. 6 shows the front view for the first embodiment, where the upper layer and a lower layer of the flap opening have been opened; and,

FIG. 7 is a back view thereof.
